UNITED STATES PATENT OFFICE.

GIDEON FRISBEE, OF READING, PENNSYLVANIA.

IMPROVEMENT IN CORE-LIFTERS FOR ANNULAR ROCK-DRILLS.

Specification forming part of Letters Patent No. **147,492**, dated February 17, 1874; application filed January 21, 1874.

To all whom it may concern:

Be it known that I, GIDEON FRISBEE, of Reading, in the county of Berks and State of Pennsylvania, have invented a new and useful Improved Core-Lifter for Annular Rock-Drills; and I do hereby declare the following to be a full, clear, and exact description thereof, which will enable others skilled in the art to which it appertains to make and use the same, reference being had to the accompanying drawing, which forms a part of this specification, and in which—

Figure 1 is a section taken through the axis of the core-lifter and annular drill to which it is attached; and Fig. 2 is a transverse section taken on the line *x x*, Fig. 1.

The same parts are denoted by the same letters in both figures.

This invention consists in the combination of an exterior pipe or ring, constructed with a tapering recess in its inner surface, and a ring or annular wedge inserted into said recess, and which, as the drill advances, slides over the core, but is wedged against it by the withdrawal of the drill.

A in the drawing represents the Leschot annular diamond-bit, screwed into the section *B* of pipe which contains the core-lifter, and which is in turn screwed into the core-barrel or into another section of pipe. *C* is a tapered recess in the interior of *B*. *D* is the core-lifter, consisting of a cut ring of steel sprung into the recess *C*. It is tapered outside to fit said recess, and has projections *E E* on its inner sur-

face, between which the ring is filed thin so as to be elastic. These projections have small pieces of bort or carbon set in their faces to prevent them from being worn by the rock.

In operation, as the bit excavates the rock, and the core enters *D*, the latter first becomes stationary on the core, and is then forced over it by the shoulder of recess *C*, the tube *B* revolving round *D* till the required depth is reached. When the drill-rod is withdrawn, *D* is forced toward the small end of the recess, clamping the core more firmly as the tube *B* recedes, until it detaches the core from the solid rock.

The bit may itself be recessed, as above described, and the core-lifter inserted into it; but I prefer the arrangement shown, as it permits the same core-lifter to be used with different bits.

Instead of the thin ring with projections, an annular wedge may be used, made in two pieces, fitting the tapered recess.

What I claim as my invention, and desire to secure by Letters Patent of the United States, is—

The combination, operating substantially as described, of an annular core-lifter and a tube or ring constructed with a tapering recess in its inner surface.

GIDEON FRISBEE.
